METHOD OF CONSTRUCTING TUNNELS

Application filed June 23, 1931. Serial No. 546,190.

My invention relates to tunnels, and particularly to methods of constructing approach trenches and approach tunnels associated with underwater tunnels. The general object of the invention is to provide an improved method of constructing tunnel approaches to underwater tunnels, comprising methods of sheeting, bracing and excavating approach trenches and laying submersible approach tunnels or tunnel sections therein, and which have advantages over methods heretofore employed in such cases where approaches have been built by ordinary compressed air methods or by open cut-and-cover methods.

To the above ends my invention consists in features of construction and arrangements hereinafter described and particularly pointed out in the claims.

The invention is especially useful when employed in constructing approaches to tunnels built in open trenches under rivers or other bodies of water, the approach tunnels being under riparian lands or streets adjacent to the main water body. I have heretofore designed and utilized certain improved methods of constructing and laying tunnel sections in such main water bodies which involve separately constructing the sections with end closures, towing these to position over dredged trenches, and sinking them under suitable control to position in the trench, the sections being subsequently joined end-to-end and opened to provide a continuous passageway through the sections constituting the tunnel.

By my present invention approach tunnel sections may be employed of the same general type as those constituting the main body of the tunnel, with resulting advantages in economy, safety, and speed in comparison with the usual compressed air or cut-and-cover methods employed in building the approaches.

An exemplification of the present invention will be described and explained in connection with the accompanying drawing, wherein

Fig. 1 is a transverse sectional view of an

approach trench, with a tunnel section in position therein;

Fig. 2 is a fragmentary plan view of the trench with abutting tunnel sections;

Fig. 3 is a fragmentary longitudinal sectional view of the trench and abutting tunnel sections, and

Fig. 4 is a fragmentary enlarged plan view of the side wall of the trench.

In carrying out my method I first drive at intervals along the outside lines or margins of the proposed trench, bracing units or master piles generally designated as 10, the space between the lines of the master piles and defining the sides of the trench being of appropriate width. Each master pile is preferably constituted of a metallic rolled beam 11, such as an I-beam or H-beam, to the back or outside marginal portions of which are secured as by riveting, sections 12 of steel sheet-piling of suitable type, the outer edge portions of which are provided with interlocking devices 12a and 12b. The master piles are driven at intervals of fifteen feet more or less and are of a length sufficient to extend from a few feet above the level of the water in the trench to be excavated, through the earth a distance of from ten to twenty feet below the bottom of the proposed trench.

Metallic sheet-piles 13, preferably of a standard interlocking steel type are then driven between the master piles, the end piles of the series being interlocked with the interlocking sections 12, thus closing the gaps or spaces between the master piles. Ordinarily in driving the series of piles 13 between two master pile units, the end piles of the series, that is those connected to the associate pile sections 12, will be driven first, followed by the next in order, the last two or three piles in the middle of the series being interlocked and driven together. Instead of being driven in a straight line between the master piles, each series of piles 13 between two of the master piles are in the form of an arc with its convexity inward. Such arc in effect may be said to be horizontally suspended at its ends, the points of suspension being the master piles 10. The trench walls proper having

been thus completed, next, horizontal braces 14 are connected to the upper portion of each pair of master piles disposed at the opposite margins of the trench, the cross braces being preferably heavy metallic rolled beams which may rest on and be secured to angle plates 14a which are fixed to the master piles. The cross braces preferably are disposed so as to afford some five feet of clearance above the 10 low water level. Upon completion of the piling operation and the bracing, the trench between the lines or walls of piling is dredged or excavated, but without being dewatered. If required, bearing piles 15 may then be driven and cut off to the grade line 15a of the 15 bottom of the trench.

The present method of constructing an approach trench is particularly adapted for use with tunnels constituted by submersible 20 sections which are towed to position in the water over the trench and between its walls of piling, and thereafter sunk and connected; and in the drawing there are shown tunnel sections 16 of this general type, provided 25 with end closures or diaphragms 17. As herein illustrated, these sections are provided with temporary buoyant shafts 18 near their ends, these shafts being applied after the sections have been towed to position and preliminary to sinking. Underlying the shaft seats 30 18a are bulk-headed spaces or flooding chambers 19. This construction enables the tunnel sections to be submerged to prepared locations under suitable control.

35 When each section has been sunk and brought to rest on the bearing piles 15 it is adjusted to position and the end diaphragm 17 of one section pulled to contact with the abutting diaphragm of the adjoining section theretofore emplaced. The shafts 18 are 40 then removed and the shaft seats 18a closed or blocked.

The trench may be then back-filled, the tunnel sections 16 entered consecutively and the 45 contacting diaphragms permanently connected as by internal riveting, after which they are cut or burned out along their inner peripheries inside the connecting rivets and the connection completed. These submerged connected sections, it will be understood, constitute the shell of the completed approach tunnel which is suitably lined as indicated at 20. While the method of constructing the trench is particularly adapted for use with a submersible tunnel of the general type described, 50 it is to be understood that in principle its use is not so restricted.

55 It is to be observed that where there is a considerable over-burden of earth, this may be excavated and braced by ordinary methods until the water level is reached, after which my improved method is to be employed. When feasible the sheet piling may be pulled up and used again or salvaged.

60 It is further to be understood that varia-

tions in detail may be employed without departing from the scope of the invention.

I claim:

1. The method of preparing an approach trench for the approach portions of underwater tunnels which comprises driving unitary breast members at intervals along the side margins of the proposed trench, each constituted by a metallic beam with metallic sheet-pile sections, driving connected metallic sheet piles between and connected to said unitary members, connecting cross braces to opposite unitary members, and dredging or excavating between the trench walls thus formed.

2. The method of preparing an approach trench for an approach portion of an underwater tunnel which comprises driving unitary breast members at regularly spaced intervals along the side margins of the proposed trench, such breast members constituted by a metallic beam and connected metallic sheet pile sections, driving metallic sheet piles in an arcuate line between each pair of adjacent unitary breast members, the breast members and sheet piles being connected and constituting in effect an inwardly curved flexible arc in horizontal cross section with the said adjacent unitary members as its points of suspension, and then connecting bracing members across the trench to opposite unitary members.

3. The method of preparing an approach trench for the approach portion of an underwater tunnel which comprises driving unitary master piles at intervals along the side margins of the proposed trench, each master pile constituted by a metallic beam with rigidly connected sheet pile sections at its side edge portions, driving connected metallic sheet piles connected to said unitary members, then connecting cross braces to the upper portions of the master pile above the water line, and then dredging or excavating between the trench walls thus formed, all without dewatering.

4. The method of preparing an approach trench for the approach portion of an underwater tunnel, which comprises defining, as by walls of sheet piling, a trench for receiving submersible tunnel sections, next excavating the material between the walls thus defined without dewatering the trench, and next bracing the trench crosswise by devices so placed as to leave the underlying water surface clear to enable tunnel sections to be floated in without interference.

5. The method of preparing an approach trench for the approach portion of an underwater tunnel, which consists in driving a series of master piles at spaced intervals along the sides of the proposed trench and to a depth well below the eventual bottom of it, each pile comprising a heavy metal beam to the sides of which sections of steel piling

have been rigidly attached to extend laterally and oppositely therefrom, then filling in the space between the master piles with loosely connected piling sections thus flexibly 5 filling the space, these loosely connected sections being connected at their ends to the master piles so that the pressure of the soil without the trench lines is transferred in

horizontal tension, then applying cross bracing to the tops of opposite master piles above the water lines so as to leave the space below free and clear, and then dredging out the material at the bottom of the trench to the required depth without dewatering. 70
